(57) **CLAIM**

The ornamental design for the battery clamp feature, as shown and described.

DESCRIPTION

FIG. 1 is a front, right, and top perspective view of the battery clamp feature showing our new design;

FIG. 2 is a rear, left, and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged view of portion 9 shown in FIG. 1.

The dash-dash broken lines in the drawings depict portions of the battery clamp feature that form no part of the claimed design. The dot-dash broken lines represent boundaries of the enlarged portion shown in FIGS. 1 and 9 that form no part of the claimed design.
